Patented Mar. 18, 1958

182,334

ICE TONGS

John R. Grossmann and Julien A. Thompson,
Portland, Oreg.

Application February 7, 1957, Serial No. 44,798

Term of patent 14 years

(Cl. D54—11)

FIG. 1

FIG. 2

FIG. 3

Fig. 1 is a side view of an ice tong showing our new design, the tongs being open;

Fig. 2 is an edge view of the tongs; and

Fig. 3 is a view on a reduced scale of the tongs from the side opposite that in Fig. 1 in their closed position.

We claim:

The ornamental design for an ice tong, as shown.
